TWO-WAY COLLAPSIBLE CONTAINER

Johan Simon Johnson, Chicago, Ill., assignor to Bigelow-Garvey Lumber Co., Chicago, Ill., a corporation of Illinois

Application August 19, 1954, Serial No. 451,000

6 Claims. (Cl. 217—48)

This invention relates to storage or transportation containers having a side wall unit which can be collapsed in either direction.

The main body of this invention is to provide a container side wall unit comprising hingedly connected side wall panels in which the wire loop hinges are mounted so that the unit can be folded in either of its two possible directions of fold into a substantially flat condition. Another object of this invention is to provide for a collapsible side wall unit of this type, top and bottom closure members having locking engagement therewith as well as cooperating with the unit to form a laterally rigid structure.

A more specific object of the invention is to provide a construction which facilitates the application of the top and bottom walls to the open ends of the side wall unit into locking relationship.

Other and more detailed objects of the invention will be apparent from the embodiments thereof illustrated in the attached drawings.

In those drawings,

Figure 1 shows an elevational view of the container of this invention illustrating the manner in which the top is inserted and assuming that the elevation of Figure 1 shows the front of the container;

Figure 2 is a top plan view of the container assembled;

Figure 3 is an enlarged perspective view of the upper right-hand corner of the assembled container showing how the top is locked after it is inserted;

Figure 4 is a right-hand side elevational view of the container assembled;

Figure 5 is a vertical cross-sectional view taken on the line 5—5 of Figure 4;

Figure 6 is a horizontal cross-sectional view taken on the line 6—6 of Figure 1;

Figure 7 is a detail view, partly in cross-section, showing the relative position of the associated panels at the lower left-hand corner and the upper right-hand corner of Figure 6 when folded in one direction;

Figure 8 is a similar view showing the same corners when folded in the opposite direction; and

Figures 9 and 10 are views corresponding to Figures 7 and 8 for the lower right-hand and upper left-hand corners of Figure 6.

While the type of container illustrated in the drawings employs an open slat type of wall and top and bottom construction, it will be understood that the subject matter of this invention can be applied to containers having solid or continuous wall panels.

The subject matter of this invention relates generally to that disclosed in my Patent No. 2,008,762, issued July 23, 1935, for Container, but distinguishes primarily therefrom in having corners which can fold inwardly or outwardly as distinguished from the disclosure in that patent where an opposite pair fold inwardly and an opposite pair fold outwardly so that the patented container can be folded in one direction only.

2

The open slat-like form of the walls of the container can take any particular suitable detailed form. The construction illustrated in this respect is exemplary only. As shown, the side wall unit comprises the front and back walls 10 and 12 and the side walls 11 and 13. The front and back walls have a plurality of horizontal battens of which 10^a and 12^a are examples. The side walls 11 and 13 are framed so as to have side edge framing members of which the members 11^a, 11^b and 13^a, 13^b are examples. The side wall panels 10, 11, 12 and 13 are arranged in rectangular relationship and are interconnected at adjacent corners by a series of wire loops which form hinging connections. These wire loops are shown at 16^a, 16^b, 16^c, and 16^d and lie in apertures in the adjacent members at the corners so as to lie in planes substantially at right angles to the diagonals of the rectangle. When the side wall unit is set up as shown in Figure 6 these wire loops have a planar form.

As clearly shown in Figure 6, the side wall panels are arranged in a special manner and the hinging wire loops are mounted in a special manner so that the assembled rectangular structure can be folded to a substantially flat condition in either of two directions. Examining the structure in Figure 6 in a clockwise direction, it will be noted that the trailing edge of each wall panel overlaps the leading edge of the associated panel. In a like manner the batten 10^a overlaps in part the side edge of the panel 11 starting at the lower left-hand corner of Figure 6. In the upper left-hand corner the side member 11^a overlaps in part the side edge of the panel 12 while at the upper right-hand corner the end of batten 12^a overlaps in part the side edge of the panel 13. Finally, the side framing member 13^b overlaps in part the side edge of the panel 10. Thus going around the rectangle in Figure 6 in a clockwise direction the leading edge of either a batten or a side framing member overlaps the adjacent edge of the next panel.

It is also to be noted in Figure 6 that the wire hinging loops are mounted in a particular manner so that going in a clockwise direction these wire loops do not intersect the leading edge of the wall panels but do intersect the trailing edge of the wall panels at each corner.

As a result of this special relationship of the parts, as just described, it is possible as indicated in Figures 7 to 10 inclusive to cause hinging action at each corner in either of two directions. Thus in Figure 7 for the lower left-hand and upper right-hand corners the position of the parts are shown when the adjacent panels are opened outwardly. On the other hand, in Figure 8, there is shown the relationship of these parts for these same corners when the panels are closed inwardly. In just the same way there is illustrated in Figures 9 and 10 the closed and open positions respectively for the lower right-hand and upper left-hand corners of Figure 6. Thus it is demonstrated that by the special relationship of parts it is possible to collapse the side wall unit of this invention in either of its two possible directions of movement to a substantially flat condition.

There is illustrated particularly in Figures 1, 2, 4 and 5 how the top and bottom walls 14 and 15 are constructed and mounted to be locked into the open ends of the wall unit when set up to form a complete enclosure having considerable resistance to force tending to distort the unit out of rectangular relationship. The side wall panels 11 and 13 are of similar construction and, as shown in Figure 4, in connection with panel 13 at the top and bottom thereof, there are included a pair of strips 13^d and 13^e which are secured to the panel in spaced relation. Similarly, there is provided at the bottom a pair of spaced strips 13^f and 13^g. Panel 11 is similarly constructed. The top and bottom panels consist of two groups of strips secured together in right angled relation.

so that the ends of each group extend beyond the outer faces of the outside strips of the other group. As clearly shown in Figure 5 the ends of one group are slipped in the spaces between the strips 13^d and 13^e and, as shown in Figure 2, the ends of the other group overlie the top edges of the remaining panels 10 and 12.

In order to make provision for the insertion of the top panel and, in fact, the bottom panel 15 which is similarly constructed and mounted, hinging members are omitted at certain corners of the side wall unit. Thus as shown in Figure 1 the hinging loops are omitted at the upper right-hand and lower left-hand corners of the container. As shown in Figure 4, they are omitted at the upper left-hand and lower right-hand corners of the container. Instead of these hinged loops two-part wire fastening elements are employed. These are shown at 10^b and 13^k and 10^c and 11^c in Figure 1. They are shown at 13^e and 12^b and at 10^d and 13^b in Figure 4.

As appears from Figure 3 these two-part fastening devices are in the form of wire loops having their ends passing through the adjacent parts of the panels so that they can be inter-looped to lock the corners at those points. When they are not inter-looped, as shown in Figure 1, one or the other of the associated panels can be sprung outwardly as in the case of panel 13 to facilitate the insertion of the top 14 in the position previously described. These loops are then interlocked as shown in Figure 3 to prevent the top from coming out. The bottom 15 is inserted in a similar manner. It will be clear therefore that the top and bottom members interlock with the side wall unit and are associated with it to strengthen the complete container against lateral distortion.

To further strengthen the structure, strapping strips S, as shown in Figure 1, can be attached around the periphery of the container at the top and bottom so as to overlie the interlocking wire loops and thereby prevent their separation under stress.

From the above description it will be apparent to those skilled in the art that many of the details of construction as illustrated can be varied, while retaining the novel subject matter herein disclosed. I prefer, therefore, not to be limited to the single example herein given, but only by the appended claims.

What is claimed is:

1. A collapsible container of the type described comprising a rectangular unit when erected composed of four

wall panels arranged in approximate edge to edge relation with the adjacent edges overlapping progressively around the periphery of the rectangle, an opposite pair of said walls each having horizontal battens on their outer faces extending at their leading edges only beyond the adjacent side edges of the walls to which they are attached and partially overlapping the adjacent edges of the associated panels of the remaining pairs at diagonally opposite corners, vertical framing members at the side edges of the remaining pair of walls partially overlapping the adjacent side edges of the first pair of walls at the remaining pair of diagonally opposite corners, and hinge wires lying in apertures extending through the overlapping ends of the horizontal battens and the adjacent vertical framing members, whereby said unit folds flat in either of two directions.

2. In the combination of claim 1, said hinge wires being in the form of closed loops lying in a single plane positioned substantially at right angles to the diagonals at the associated corners.

3. In the combination of claim 1, said hinge wires being positioned so as not to intersect the wall panels to which said battens are attached.

4. In the combination of claim 1, said hinge wires being positioned so as not to intersect obliquely the wall panels to which said battens are attached.

5. In the combination of claim 1, an adjacent pair of panels having pairs of attaching members secured at diagonally opposite corners, said fastening devices being separable to permit springing apart of the associated panels at those corners.

6. In the combination of claim 1, an adjacent pair of panels having pairs of attaching members secured at diagonally opposite corners, said fastening devices being separable to permit springing apart of the associated panels at those corners, said fastening devices consisting of pairs of interconnectable wire loops.
